UNITED STATES PATENT OFFICE.

HOWARD GIBSON, OF ADENA, OHIO.

BUCKLE AND CLASP ATTACHING MEANS.

No. 909,782.

Specification of Letters Patent.

Patented Jan. 12, 1909.

Application filed June 29, 1908. Serial No. 440,875.

To all whom it may concern:

Be it known that I, HOWARD GIBSON, a citizen of the United States, residing at Adena, in the county of Jefferson and State of Ohio, have invented certain new and useful Improvements in Buckle and Clasp Attaching Means; and I do declare the following to be a full, clear, and exact description of the invention, such as will enable others skilled in the art to which it appertains to make and use the same.

This invention relates to buckle and clasp attaching means and has for its object to provide means whereby a buckle or clasp may be readily attached in detachable position to replace the old one, if broken or otherwise rendered unfit for service.

A further object of the invention is to provide attaching means whereby the buckle or clasp may be attached to the harness after the same is otherwise complete.

With these and other objects in view, the invention consists of certain novel features of construction, combination and arrangement of parts, as will be more fully described and particularly pointed out in the appended claims.

Figure 1, is a view of my improved attaching means as applied to a clasp; Fig. 2 is a side elevation thereof; Fig. 3 is a vertical section on line 3—3 of Fig. 2; Fig. 4 is a detail perspective view of the coupling pin; Fig. 5 is a plan view showing the application of my improved attaching means to a buckle; Fig. 6 is a side elevation thereof; and Fig. 7 is a vertical section on line 7—7 of Fig. 6.

In the embodiment illustrated the numeral 1 indicates a clasp of ordinary construction provided with an approximately U-shaped body 2, of spring metal. The improved attaching means consists of a coupling pin 3, having a recessed head 4, adapted to be engaged by a screw-driver or other tool, and at its opposite end with a laterally projecting lug 5, the arms 6 of the body 2, of the clasp having central transversely alining apertures 7, to receive the body of the pin and alining recesses 8, in the walls of said apertures to receive the lug 5, thereof. One 50 of said arms 6, is also provided in its outer face at its apertured portion with an annular recess 9, and with a socket 10, in its recess 9, directly opposite its recess 8, to receive the lug 5, of the coupling pin. The socketed

portion of said last mentioned arm is bent 55 slightly outward, as clearly shown in the drawing, so that after the lug of the coupling pin has been inserted through the recess 8, of said arm, the socketed portion thereof is pressed slightly inward by the lug riding 60 in the annular recess 9, during the operation of turning the coupling pin a half revolution by a screw-driver or other suitable tool, to bring said lug in position to enter its socket 10, after which the socketed portion of said 65 arm is permitted to spring outward into its normal position and holds the lug of the coupling pin in position in said socket.

A roller 11 is revolvably mounted upon the pin, said roller having a central bore 12, to 70 receive the body of the pin, and a longitudinal recess 13, in the wall of its bore to receive the lug of the coupling pin, during the operation of mounting the roller in position.

When my improved attaching means is applied to a buckle instead of a clasp the side pieces 14 of the former are also apertured and recessed similar to the manner shown in connection with the clasp and the 80 tongue 15 of the buckle provided with a recess 16, the purpose of which will be understood. The apertured portion of one of the side pieces of the buckle is also bent outward, as at 17, to hold the lug of the coupling pin in position in its socket, as heretofore explained, and the apertured portion of the other side piece is provided with an annular socket 18, to receive the head of the 85 coupling pin.

From the foregoing, it will be observed that by employing my improved attaching means, the buckle or clasp may be readily placed in position should the old one break or otherwise be rendered unfit for service or 90 instead of sewing and riveting the buckles or clasps in position when used in connection with harness they may be readily applied in a detachable position after the harness is otherwise complete. It is also to be understood that there are numerous other instances where my attaching means may be applied.

From the foregoing description taken in connection with the accompanying drawings, the construction and operation of the 105 invention will be readily understood without requiring a more extended explanation.

Various changes in the form, proportion

and the minor details of construction may be resorted to without departing from the invention, as defined in the appended claims.

Having thus described my invention, what I claim as new is:

1. In combination with a fastening device having spaced resilient side pieces formed with central transversely aligned apertures, alining recesses in the walls of said apertures, and one of said side pieces with a socket in its outer face directly opposite its recess, a coupling pin having a lateral lug adapted for reception by said recesses and to seat in said socket, and a roller revolvably mounted upon the coupling pin, the former having a longitudinal recess in its bore to receive the lug of the latter.
2. In combination with a fastening device having spaced resilient side pieces formed

with central transverse aligned apertures, 20 alining recesses in the walls of said apertures and one of said apertures with a socket in its outer face, a coupling pin having laterally projecting lugs adapted for reception by the transverse recesses of said side pieces 25 and to seat in said socket when in inserted position, the socketed side piece being bent outwardly at its apertured portion, and a roller revolvably mounted upon said pin and having longitudinal recesses in its bore to 30 receive the lug thereof.

In testimony whereof I have hereunto set my hand in presence of two subscribing witnesses.

HOWARD GIBSON.
